UNITED STATES PATENT OFFICE.

FRANCISCO ANGEL QUIROZ, OF NEW YORK, N. Y.

CENTRIFUGAL APPARATUS FOR SEPARATING PURPOSES.

Application filed April 23, 1926. Serial No. 104,146.

My invention relates to centrifugal apparatus for separating purposes and particularly to centrifugal apparatus for separating solid particles suspended in a liquid.

5 The object of my invention is to provide a centrifugal apparatus to separate in a continuous operation solid particles suspended in liquids, whether said solid particles are of more specific gravity than the 10 liquid, whether they are of less specific gravity than the liquid or whether they are of the same specific gravity as the liquid.

Another object of my invention is to provide a centrifugal apparatus for separating 15 purposes of very simple construction, which has no screw conveyor inside of the container nor any moving mechanism inside of the rotating container, therefore eliminating all the disadvantages found in separators of that kind.

A further object of my invention is to avoid the grinding of the solids which are being separated, by any moving parts operating inside of the rotating container; this 25 is very objectionable in the separation of sugar, salt and other materials which are produced in a crystal form.

It will be noticed that instead of removing by any mechanical means the solids 30 which are pressed against the walls of the container by the centrifugal action, and dragging them along the walls of said container in order to remove them from the place where they were settled by the centrifugal force, I reverse the centrifugal action on the spot where said solids are settled, by which means the said solids are pushed 35 away and out from the same walls on which they were lying; the same centrifugal force 40 which presses the solids against the walls on one side of the container, removes the same solids on the other side of the container. The reversing of the centrifugal action in the container is accomplished by 45 rotating said container around an axis placed eccentrically to its own axis of rotation.

For an illustration of several of the many forms my invention may take, reference is 50 to be had to the accompanying drawings in which—

Fig. 1 is a longitudinal sectional view, partly in elevation, of an apparatus embodying my invention, and having two con-

tainers. This form of apparatus, probably, 55 will be more commonly used.

Fig. 2 is a longitudinal sectional view, partly in elevation, on the line AA of Fig. 1.

Fig. 3 is a longitudinal sectional view, 60 partly in elevation, of an apparatus embodying my invention, having only one container and a different arrangement for disposing of the liquid, but using the same principle of reversing the centrifugal action, which is the spirit of this invention, as will be 65 hereafter described and claimed.

Fig. 4 is a right front view of the apparatus shown in Fig. 3.

Fig. 5 is a sectional view of one of the 70 rotary bowls of the apparatus at the center and at right angle to its axis, which shows another arrangement for the liquid openings which also will be described hereinafter.

Fig. 6 is a sectional view of a container 75 showing the direction of the lines of force, to which the discharging solids and liquids are subjected. These lines of force are very important, in order to clearly understand the principle of my invention.

Fig. 7 is a sectional view of a container 80 showing the position of the screens in the container and the direction of the lines of force of the liquid as it leaves the container.

In the process of separating suspended 85 solids in liquids by means of centrifugal force, a bowl or chamber which contains the mixture is rotated at a suitable speed, usually the solids, being of greater specific 90 gravity, are pressed by centrifugal action against the wall at the periphery of the 95 container, and by some mechanical means, like a screw conveyor or other mechanism, the solid particles are carried from the zone covered by the liquid to another zone out 100 of the liquid where they are disposed of. In this process the solid particles are removed by mechanical means which act 105 against the pressure produced by the centrifugal force, and which is always tending to pull the solid particles toward the periphery of the container. In other words, in a rotating bowl which rotates on a central axis, the centrifugal force tends to press the solids all around the periphery of said container or bowl and can only be directly removed by some other force which acts independently from the centrifugal force. In the apparatus embodying my inven-

tion, the centrifugal force presses the solid particles only against one part on the inner side of the wall at the periphery of the container or bowl, while at the opposite side 5 of said container or bowl the same centrifugal force throws away from the same wall and toward the axis on which the container rotates itself the same solid particles which are being pressed at the other side 10 of the container.

Similar numerals refer to similar parts throughout the several views and several forms of the apparatus.

One form of the apparatus embodying 15 my invention is shown in Fig. 1. It comprises a rotating member 1, a rotating hollow shaft 2 which may form an integral part of member 1, as shown in the drawing. On the rotating member 1, and eccentrically 20 to its axis are mounted the shafts 3, firmly secured to member 1, by nuts 4, and having extensions 5, which form the axis on which bowls 6 are mounted and made to rotate by means of a gear 7, which is mounted on shaft 25 9, and acts on the gears 8, which form an integral part of the bowls 6. It will be apparent that the bowls 6 will rotate around the axis 5 in proportion to the differential of speed at which shaft 2 and shaft 9 will rotate. If the speed at which shaft 9 rotates 30 is greater than the speed at which shaft 2 rotates and the rotation of shafts 9 and 2 is in the direction shown by the arrows 40, shown in Fig. 2, the direction at which the bowls 6 will rotate is shown by the arrows 41 shown in Fig. 2. Another extension 10, provides the means for securing firmly the receivers 11 to the extension 5 of the shaft 3, so that said receivers 11 will always be in 40 the same position in regard to the member 1, and to the axis on which said member 1 rotates. The seats on said receivers 11 firmly secured by nuts 12, prevent the bowls 6 from coming out from the axis 5 and keeps 45 them in position.

Mounted inside of bowls 6 and forming an integral part thereto, a suitable number of vanes 13 are set at a convenient angle, so as to form pockets which will carry the solid 50 particles from outer end of the bowls to the inner end of the same, when the bowls move around their own axis 5 by means of shaft 9 and gear 7.

A member 15 is mounted to the extensions 55 14 which form an integral part of the rotating member 1, and firmly secured thereto by means of nuts 42 clearly shown in Fig. 4. Said member 15 has a small chamber 16 to receive the liquid which is to be treated, said 60 liquid being supplied by pipe 18. Extending from chamber 16 there are pipes 17, one for each bowl, which object is to convey the liquid from chamber 16 to the inside of the bowls 6 discharging the liquid at 19, shown 65 in Figs. 2 and 4. The member 15 is mounted

in such a manner so as not to interfere with the rotation of the bowls 6 on their axis 5. It is apparent that the liquid which gets into chamber 16 will be thrown by centrifugal force away from the axis of rotation of said 70 chamber 16, which axis is the same as that of the rotating member 1, and will be forced through the pipes 17 and finally discharged into the bowls 6 and at a point 19, shown in dotted lines in Figs. 2 and 4. 75

The receivers 11 which are secured on shaft 5 by means of nuts 12 and bolts 20 can be adjusted to any desired position, in order to properly receive the solid particles at the proper place around the periphery of the 80 bowls 6 and to switch them outside of the bowls 6 where they can be received by any suitable means.

In Fig. 6 I show a container working under the same principle as the one shown in Fig. 5, with the only difference that the screens 43 which are mounted on the vanes 13 are more clearly shown, and that in this figure I also show the lines of centrifugal force 50. These lines 50 will greatly help 90 to understand my invention. They show the direction followed by the liquids and solids when leaving the pockets formed by the vanes, at any position in which said vanes happen to be in regard to the external 95 axis of rotation, about which the container rotates. This direction will always be radial in regard to the external axis of rotation, as shown at 44, but will vary in regard to the container according to the position of the 100 vanes in regard to the lines of force, at the time the liquids or solids are discharged from the vanes. It will be clearly understood that the solids can be discharged into the receiver 11 only between the lines of 105 force 50^A and 50^D as shown at 54.

It is apparent that in order to carry the solids away from the liquid zone between points 64 and 65 and empty them into the receiver 11, the vanes 13 have to be set at 110 an angle in regard to the radius of the container, having its center at the internal axis of rotation 62, and toward the direction of rotation of said container about its own axis, to form pockets as shown by the vane 45, the wall of the periphery 47 and an arc line 46 which center is the external axis 61. Said arc line 46 cuts the point of contact of the tangential line of force 50^A and the periphery of the container at 60, and also makes contact with the end of the vanes at 66. The solids can only be thrown into the receiver 11 by the vanes 13 when said vanes pass the arc line 46 and get into the zone between the lines of force 50^B and 50^D. It is apparent that if the vanes 13 are set in a radial position about the internal axis 62, there will not be any solids left in the pockets by the time the vanes 13 reach the point 60, because they would have been thrown out by 120 125 130

the action of the centrifugal force in the direction of the lines of force shown at 44. It is also obvious that the receiver can not be extended outside of the lines of force 50^b 5 and 50^b, because it will be in the way of rotation of the vanes 13 about the internal axis 62; therefore solids must be emptied by the pockets into the receiver 11 during the time the vanes 13 move from point 66 to point 67 10 in rotation about the internal axis 62.

In Fig. 7 I show a container which works under the same principle as the one shown in Fig. 3 and Fig. 4 with the only difference that it shows the direction followed by the 15 liquid when leaving the container, which direction is the same as the lines of force 53, and also shows in a clearer way the screen 43 on the vanes which form the pockets, and the screen 51 forming the periphery of the 20 container.

The operation of the apparatus is as follows:—The apparatus may be mounted on any suitable bearing not shown, may be operated in any desired position, vertical, horizontal or at any angle. The hollow shaft 2 is made to rotate by any suitable means, and at any convenient speed. At the same time shaft 2 mounted inside of the hollow shaft 2 is also made to rotate, it may rotate faster 25 or slower than the shaft 2 but in case it rotates slower the bowls 5 will rotate in the opposite direction and the position of the pockets and vanes should be reversed. It is obvious that any differential of speed between shaft 9 and shaft 2 will cause the gear 30 7 to rotate to one direction or another in relation to member 1, on which bowls 6 are mounted; therefore the bowls 6 will also rotate on their own axes 5 by means of gear 7 35 acting on gears 8 which form an integral part of the bowls 6. It is apparent that the rotation of the bowls 6 on axis 5 will be accomplished regardless of the speed at which member 1 will rotate, as long as there is a 40 differential of speed between shaft 2 and shaft 9.

While the whole apparatus is in action, the liquid to be treated is supplied by pipe 18 and discharged inside of chamber 16. Due 45 to the centrifugal force produced by the rotation of the apparatus the liquid will be forced to follow through the pipes 17 and finally will be poured inside of the bowls 6. By the centrifugal action of the rotating member 1 on which the bowls 6 are mounted, the liquid will only be stored on one side of the bowls as shown at 22. The same centrifugal action will cause the solids to be pressed against the outer side of the wall at 50 the periphery of bowls 6 where vanes 13 forming a pocket will catch said solids and convey them around to the opposite side, when the centrifugal action on the wall is reversed, and instead of pressing the solids 55 against the wall, they will be pushed away 60

from said wall and into the receivers 11 which will lead them out of the bowls. Any liquid caught in the pockets formed by vanes 13 and together with the solids will gradually overflow from said pockets as they are turned around to a reverse position, or will filter through conducts provided in the vanes as shown in Fig. 5 at point 27 and only the dry solids will be carried around to be poured on the receivers 11 and out of the apparatus. The liquid, free from solids, may be overflowed over the edge at 23 shown in Fig. 1 or may be forced through conducts 70 24 on the wall forming the periphery of the same as shown in Figs. 3 and 4. The angle of the position of the receivers 11 may be changed at will to suit conditions. 75

While the apparatus can be constructed with a plurality of bowls 6 placed around the member 1, it can also be constructed with 80 only one bowl as is shown in Fig. 3 but in this case it is advisable to place a weight not shown on the arm 30 at the opposite side of the location of the bowl 6 so as to balance the apparatus and avoid vibrations in the 85 machine. Another object of letting the liquid filter out through the walls of the bowls as shown at 24 in Figs. 3 and 4, instead of letting the liquid overflow as shown at 90 23 in Fig. 1, is to enable the apparatus to 95 separate solid particles of less specific gravity than the specific gravity of the liquid as well as particles of greater specific gravity than the liquid.

In Fig. 3 I show the bowl 6 mounted firmly on the shaft 25 which rotates on bearing 26 formed by the member 1, instead of rotating on the shaft 5 as shown in Fig. 1. Also I show in Fig. 3 the receiver 11 mounted on and forming an integral part 100 of member 15 instead of being mounted on the shaft 5 as shown in Fig. 1.

What I claim is:

1. A centrifugal separator comprising a 105 container, rotatable in a fixed orbit and also about its own axis, having vanes or ribs extending from one end to the other of the container in such a way that they form pockets at its periphery, said ribs or vanes being set at an angle to the radial line of the container and toward the direction of rotation of the container about its own axis, having means for introducing the material inside the container, means for withdrawing the liquids and means for withdrawing the solids out of the container. 110

2. A centrifugal separator comprising a 115 container, rotatable in a fixed orbit and also about its own axis, having a plurality of pockets placed around the periphery of the container, and formed by the wall around the axis of rotation of the container, ribs 120 extending in the direction of the axis of rotation, and inturned flanges bending towards the internal axis of rotation at the 125 130

ends of the container, having means for introducing material, means for withdrawing the liquids out of the container, and means for withdrawing the solids out of the container.

3. A centrifugal separator comprising a plurality of containers rotatable about an external axis and also about their own axis having a plurality of depressions located at

10 the periphery of the container, and formed by a wall surrounding the internal axis of rotation, ribs extending in the direction of the axis of rotation, and inturned flanges at the ends of the container, having means for introducing material, means for withdrawing the solids out of the container, and means for withdrawing the liquids out of the container.

4. A centrifugal separator comprising a 20 container rotatable in a fixed orbit and also about its own axis, having means for introducing material, means for withdrawing the solids and means for withdrawing the liquids, having a plurality of pockets located at the periphery of the container formed by a perforated wall around the axis of rotation, vanes extending in the direction of the axis of rotation from one end to the other of the container and inturned flanges 25 at the ends of the container.

5. A centrifugal separator comprising a plurality of containers, rotatable about an external axis and also about their own axis, having means for introducing material, 35 means for withdrawing the solids and means for withdrawing the liquids, having a plurality of depressions formed by porous walls located around the internal axis of rotation, inturned flanges closing the ends and ribs 40 extending from one end to the other of the container about the direction of the internal axis of rotation of the container.

6. A centrifugal separator comprising a plurality of containers rotatable about an 45 external axis and also about its own axis, having a plurality of pockets placed around the central axis of rotation and made up by

a wall around the central axis of rotation, walls turned inward and toward the central axis of rotation and perforated vanes connecting the inward turned walls with each other, means for introducing material inside of the container, means for withdrawing the solids out of the container and means for withdrawing the liquid out of the container.

7. In a centrifugal separator, a container rotatable about an external axis and also about its own axis, having a plurality of pockets located around the internal axis of rotation and formed by the wall forming the sides of the container, walls at the ends and ribs extending between the ends, in combination with a receiver therein.

8. In a centrifugal separator, a container 65 rotatable about an external axis and also about its own axis, having a plurality of pockets placed around the internal axis of rotation, and formed by the wall around the internal axis of rotation, walls turned 70 inward and toward the internal axis of rotation and porous vanes connecting the inward turned walls between each other.

9. In a centrifugal separator, a container 75 rotatable about an external axis and also about its own axis, having a plurality of pockets placed around the internal axis of rotation and made up by a perforated wall around the internal axis of rotation, walls turned inward and toward the internal axis 80 of rotation, and vanes connecting the inward turned walls between each other.

10. In a centrifugal separator a container 85 rotatable about an external axis and also about its own axis having a plurality of pockets placed around the central axis of rotation and formed by a porous wall around the central axis of rotation, porous inward turned walls, and porous vanes connecting the inward turned walls between themselves.

Having described and claimed my invention, I hereto affix my signature this 22nd day of April, 1926.

FRANCISCO ANGEL QUIROZ.
